UNITED STATES PATENT OFFICE.

MARCY L. WHITFIELD, OF MEMPHIS, TENNESSEE, ASSIGNOR, BY DIRECT AND MESNE ASSIGNMENTS, TO THE WHITFIELD COMPANY, OF LAKEVIEW, MISSISSIPPI.

COMPOUND PRESSURE-ENGINE.

SPECIFICATION forming part of Letters Patent No. 678,820, dated July 16, 1901.

Application filed October 7, 1898. Serial No. 692,902. (No model.)

To all whom it may concern:

Be it known that I, MARCY L. WHITFIELD, a citizen of the United States, residing at Memphis, in the county of Shelby and State of Tennessee, have invented a certain new and useful Compound Pressure-Engine, of which the following is a specification.

This invention has relation to that type of steam or like motive-fluid engines known as 10 "trunk" or "telescopic" engines, comprising a stationary low-pressure cylinder, a stationary abutment or piston, and a main moving hollow piston working in said stationary cylinder and on said stationary piston and 15 constituting the high-pressure cylinder and driving element of the engine.

The invention has for its object certain improvements in the type of engines referred to, hereinafter fully described, and specifically 20 pointed out in the claims.

In the drawings, Figure 1 is a longitudinal sectional view of a vertical engine embodying my present improvements; Fig. 2, a side elevation of the same; Fig. 3, a side elevation 25 of a horizontal engine embodying my present improvements; Fig. 4, a side elevation of the plunger which co-operates with the high-pressure cylinder formed in the piston; Fig. 5, a top view of said plunger; Fig. 6, a section on the line 6 6 of Fig. 1; Fig. 7, a side elevation of the main piston removed from its cylinder, and Fig. 8 a similar view 30 taken at right angles to Fig. 7.

In all of the above views corresponding 35 parts are represented by the same letters and numerals of reference.

The engines illustrated in Figs. 1, 2, and 3 are in general respects of well-known vertical and horizontal types.

40 My present improvements can be applied to all forms of motor devices in which the movement of a reciprocating piston performs work, and includes not only motors for driving rotating shafts, but also industrial tools—45 such as rock-drills, pluggers, &c.—wherein the reciprocations of the piston perform the work directly.

A represents a cylinder which is of the desired diameter and which is of any suitable 50 type. This cylinder is closed at one end by

a head B, secured in place in the usual way. At the side of the cylinder A is a valve-chest C, containing a suitable valve, one illustration of which will be described.

The valve-chest C is provided with a head 55 X at one end and with a guide-box at the other, in which a valve-stem e reciprocates. I illustrate within the valve-chest C a hollow balanced slide-valve E, fitting snugly within the valve-chest. Leading into the 60 valve-chest C is a high-pressure steam-pipe 1, which co-operates with an annular channel or pocket 2 on the valve E. This pocket or channel is adapted to place the high-pressure pipe 1 in communication with a port 3 in the 65 wall of the cylinder and through which steam will be admitted to the high-pressure space F. The said valve E is also provided with a pocket or recess 4, adapted to be placed in communication with the port 3, and with a third annular pocket or recess 5, adapted to be placed 70 in communication with a port 6 in the main cylinder leading to the low-pressure space G therein. The valve E is adapted to place the port 6 in communication with an exhaust-pipe 7, through which steam may be exhausted 75 from the low-pressure cylinder. The valve E is provided with a chamber h' therein, and the annular pockets or recesses 4 and 5 communicate with said chamber by means of 80 small openings 8. The valve-stem e is operated in any suitable way—as, for example, by a connecting-rod M, connected to an eccentric N on the shaft P.

Although valve mechanisms differing in 85 form from that which I have described may be employed, yet I prefer said described valve mechanism on account of its great simplicity and its not being liable to get out of repair.

Mounted in the cylinder A, so as to reciprocate therein, is a long piston D, which for purposes of lightness may be provided with a chamber b' therein. The high-pressure cylinder or space F is formed within this piston, and in line with the port 3 the piston 95 is provided with a longitudinal recess H, by means of which the said high-pressure space will be maintained in communication with said port during the movement of the piston 95 for the reason to be explained.

The piston D is provided with two bifurcated extensions or arms K, which are preferably shouldered at k and which are connected at their lower ends to a wrist-pin L, on which a connecting-rod l is mounted, the said connecting-rod engaging with the crank O on the shaft P, which latter may, if desired, be provided with one or more fly-wheels Q. Mounted within the piston D and maintained stationary with respect to said piston is a plunger J, the upper end of said plunger forming one end wall of the high-pressure space F. The plunger J is provided at its outer end with a flange j, having two recesses j' therein, in which recesses the arms K of the piston are adapted to reciprocate. The flange j of the plunger J is bolted to extensions I of the cylinder A, such extensions being provided with flanges i i, which coincide with the flange j, and between said flanges i i are the spaces k', corresponding with the recesses j' and in which the arms K reciprocate. By mounting the arms K of the piston between the extensions I of the cylinder I obtain an effective guide for said piston, by which it will always be maintained in the proper alignment with the cylinder. If desired, the bed-plate S of the engine may be provided with extensions T, having flanges t, which coincide with the flanges i and j, all of said flanges being secured together by the same bolts. The bearings R for the shaft P may be of any suitable character. The piston D and the plunger J will be preferably provided with suitable packings p', by which the necessary tightness of the joints will be secured.

An engine such as I have thus generally described and which is a convenient illustrative type of my invention will operate as follows: With the position of the parts shown in Fig. 1 the piston D has completed its high-pressure stroke, the high-pressure steam has been cut off by the closing of the port 3 from the pipe 1, and the valve E is about to be moved quickly upward to bring the pocket or recess 4 in line with said port and to bring the pocket or recess 5 in line with the port 6. This movement of the valve takes place just as the crank passes the dead-center. Steam from the high-pressure chamber will therefore pass upon expansion through the pocket H, port 3, recess 4, perforations 8, chamber h', perforations 8, pocket 5, and port 6 into the low-pressure cylinder G, and by reason of the larger diameter of that space the steam in expanding will force the piston toward the plunger J, completing one half-stroke of the piston. When the piston has completed this stroke and as the crank again passes its dead-center, the valve E will be shifted quickly to cut off the port 3 from the pocket 4 and to place the pocket 2 in communication with said port, said pocket being always in communication with the high-pressure pipe. High-pressure steam

will therefore enter the high-pressure cylinder and working against the stationary plunger J will force the piston D toward the cylinder-head B, thus completing the other half-stroke 70 of the crank. During this movement the port 6 will be in communication with the exhaust-pipe 7, and the exhaust from the low-pressure cylinder will thus be secured. By providing the piston D with an extended longitudinal 75 pocket H the high-pressure steam may be admitted to the high-pressure cylinder at all times irrespective of the position which the piston may occupy with respect to the port 3. The same is true when the steam in expanding 80 passes from said high-pressure cylinder into the low-pressure cylinder.

Having now described my invention, what I claim as new, and desire to secure by Letters Patent, is as follows:

1. In a compound engine, the combination of a main inclosing cylinder, a hollow piston mounted in said cylinder whereby the space between the piston and the cylinder head forms a low-pressure chamber, a relatively 90 stationary plunger mounted within the piston whereby the space between the piston-head and plunger forms a high-pressure chamber, a port in the cylinder, an elongated pocket on the piston in perpetual communication with said port whereby steam may be admitted into or expanded from the high-pressure chamber during the movement of the piston, and a hollow cylindrical slide-valve having pockets therein arranged to be brought 100 into coincidence with said port and with a port leading to the low-pressure chamber, substantially as set forth.

2. In a compound engine, the combination of a main inclosing cylinder, a hollow piston mounted in said cylinder whereby the space between the piston and the cylinder head forms a low-pressure chamber, a relatively stationary plunger mounted within the piston whereby the space between the piston-head and plunger forms a high-pressure chamber, a port in the cylinder, an elongated pocket on the piston in perpetual communication with said port whereby steam may be admitted into or expanded from the high-pressure chamber 105 during the movement of the piston, and a hollow cylindrical slide-valve having pockets therein arranged to be brought into coincidence with said port and with a port leading to the low-pressure chamber, said slide-valve 110 having a high-pressure pocket or recess 115 therein by which steam may be successively admitted to and cut off from the high-pressure chamber, substantially as set forth.

3. In a compound engine, the combination 125 of a cylinder, a hollow piston mounted therein, a plunger working in said piston, a valve mechanism for admitting steam into the high-pressure chamber and for allowing steam to expand from the high-pressure chamber into 130 the low-pressure chamber, extensions carried by the cylinder and to which said plunger is

connected, and bifurcated arms on the piston working in and guided by said extensions, substantially as set forth.

4. In a compound engine, the combination of a cylinder, a hollow piston mounted therein, a plunger working in said piston, a valve mechanism for admitting steam into the high-pressure chamber and for allowing steam to expand from the high-pressure chamber into the low-pressure chamber, extensions carried by the cylinder and to which said plunger is connected, bifurcated arms on the piston

working in and guided by said extensions, an engine-frame connected to said extensions, a shaft in said frame, and connections between the shaft and said bifurcated arms, substantially as set forth. 15

This specification signed and witnessed this 22d day of September, 1898.

MARCY L. WHITFIELD.
